OR D18,960 EX

DESIGN FOR A PICTURE-SUPPORT.

UNITED STATES PATENT OFFICE.

SEYMOUR A. CURTIS, OF STRATFORD, CONNECTICUT.

DESIGN FOR A PICTURE-SUPPORT.

SPECIFICATION forming part of Design No. 18,960, dated **March 12, 1889.**

Application filed February 13, 1889. Serial No. 299,743. Term of patent $3\frac{1}{2}$ years.

To all whom it may concern:

Be it known that I, SEYMOUR A. CURTIS, of Stratford, in the county of Fairfield and State of Connecticut, have invented and produced 5 a new and original Design for a Picture-Support, of which the following is a specification, reference being had to the accompanying photograph, forming part thereof.

The leading feature of my design consists 10 of the representation of a longitudinal segment of a tree, showing the bark on its convex surface, the ends of said segment being beveled and showing the grain of the wood.

In the accompanying photograph is repre-

sented a longitudinal segment of a tree showing 15 the bark on its convex surface, the ends of said segment being beveled and showing the grain of the wood. A picture is shown on the said convex surface.

I claim—

20

The design for a picture-support, substantially as herein shown and described.

In testimony whereof I affix my signature in presence of two subscribing witnesses.

SEYMOUR A. CURTIS.
